DETENT MECHANISM

Chester A. Macomic, Chicago, Ill., assignor to
 Macomic Corporation, Chicago, Ill., a corpora-
 tion of Delaware

Application September 13, 1935, Serial No. 40,427

17 Claims. (Cl. 199—7)

My invention relates to detent mechanisms adapted for use in connection with pattern setting machines and the like, and especially adapted for use in connection with line and type casting 5 and type setting machines.

Among the objects of my invention are to provide a driving connection means adapted to be associated with a plurality of separate driven members, all driven from the single moving element and so disposed that separate driven members may be released and locked in released position with a minimum of resistance. Other objects of the invention are to provide a specially sensitive and positive detent mechanism. Other objects of 15 the invention will appear from time to time in the specifications.

My invention is illustrated more or less diagrammatically in the accompanying drawings wherein—

20 Figure 1 is a side elevation of an apparatus embodying my detent mechanism;

Figure 2 is a front elevation of the mechanism shown in Figure 1;

Figure 3 is a plan view of the machine shown 25 in Figure 2;

Figure 4 is a longitudinal section through the machine, showing the detent in the driving position;

Figure 5 is a similar section showing the detent 30 about to be released and the movable member about to be locked in place;

Figure 6 is a similar view showing release complete; the movable member being locked in position;

35 Figure 7 is a side view showing the detent at the end of the stroke and about to be re-engaged;

Figure 8 is a similar section showing the detent again engaged on the return movement;

Figure 9 a section along the line 9—9 of Figure 40 2 illustrating the parts near the end of the return stroke and about to be reset for the driving position;

Figure 10 a perspective of the serrated bed along which the detent mechanism travels;

45 Figure 11 a section through the bed.

Like parts indicated by like characters in the specification and drawings.

I have illustrated my invention as applying to a line or type casting or type setting machine, but 50 it will be entirely obvious that the mechanism might be satisfactorily used in connection with a large number of devices wherein single elements are driven in unison by a movable member and released therefrom selectively, to be later picked up upon the return movement of the driving mem-

ber; and where in the specification and claims I use language directed to type setting and type casting, I want it understood that such language is used for purposes of illustration, not to narrow the intent of my invention, which is broad enough to cover any device where such detent mechanism can be appropriately used.

As a practical application of my invention, it may be employed in connection with pattern setting mechanism such as is shown for example in 10 my previous Patent 1,775,822, issued on September 16, 1930. It will be understood that any suitable means, for example a typewriter, may be employed to depress a pattern pin. I illustrate in Figure 6 a plurality of such pins B. Each such pin is normally in the withdrawn position in which most of them are shown in Figure 6. Any suitable means, for example such mechanism as is shown in the above mentioned Patent 1,775,822, may be employed for depressing pins as shown 15 for example in the depressed position B¹ of Figure 6. A practical application of my invention is to use with pattern beds in which there is a line of pins extending longitudinally along the pattern bed, for each possible space or part of a given line of type. Assume that a page having 30 letter or letter spaces in width is required, then there will be 30 parallel lines of pins B. In each line there is a pin for each character which can be cast or set. For example, where a typewriter control is used there will be one pin, in each line or row of pins, for each character of the typewriter. As shown in Figure 6, this pattern bed, generally indicated as B², with its pattern pins B, overlies the below described matrix bed.

35 A A are side frames supporting a matrix bed, A¹. Projecting upwardly from this matrix bed A¹ are side walls A². This matrix bed for part of its length is, as shown for instance in Figures 1 and 2, smooth on its upper surface. Toward the other end the matrix bed is recessed and contains a plurality of serrated strips, A³, which strips are flush with the surface of the bed, and when assembled, as indicated especially in Figure 11, form across the bed a plurality of serrations A⁴, having curved walls on one side, and overhanging walls on the other, as indicated mounted for reciprocation along the matrix bed between the walls A² adapted to travel along the surface of the bed, and serrated strips are a plurality of matrix or type bars A⁵. These type bars are notched, as indicated on their under sides. If type bar takes the form of a matrix against which the character is cast, then those of course will be found in the bottoms of the notches. If, on the 40 45 50 55

other hand, they are type bars from which, for instance, impressions may be struck, then the impressions or characters will be found not in the bottoms of the notches, but on the ends of the 5 lugs formed by the notches or grooves, and under some circumstances, of course, these bars instead of being continuous could be made up of a plurality of separate sections or elements in line movable longitudinally. It will be understood that 10 there is one of these matrix or type bars in line with each of the serrated strips, although of course the bed could be formed either from serrated strips, or by notching or serrating a solid block, or even by cutting such notches across the bed itself. It will be understood, of course, that there 15 is a matrix or type bar A⁵ for each line of pins B. As a matter of convenience, each line of pins may overlie and conform generally to the thickness and position of the particular matrix or type bar 20 A⁵. Associated with each matrix strip is a latch member A⁶. This latch member is located in the same plane as the strip and is pivoted thereto at its end as at A⁸, for movement in the plane of the strip. Each latch member carries a downwardly 25 extending tooth A⁷, adapted to engage one of the notches A⁴. Each such latch has a releasing cam member A⁹ on one side of the pivot, and a locking cam member A¹⁰ on the other side of the pivot. There projects upwardly from each matrix strip, 30 immediately adjacent the releasing cam member A⁹, a lug A¹¹.

The matrix strips A⁵, each with its latch A⁶, are aligned in parallelism and extend longitudinally along the bed A³. The actuating means for 35 moving the matrix strips in relation to the bed and also for locking the matrix strips in relation to the bed, are as follows, C C¹ indicate racks which extend along the sides of a base A. These racks, as will be clear from Figure 2, are confined 40 upwardly by the cover plates C²⁰. Any suitable gear or gears may be employed, not herein shown, for imparting longitudinal movement to the racks C C¹ by meshing with the teeth thereof, the two racks being connected by the below described 45 structure, and moving at all times in unison. Secured to each rack is a bracket or side member C². Slidably mounted on each of said brackets is a cam plate C³. Each such plate has a lower slot C⁴, shown as horizontal, and an upper cam 50 slot generally indicated as C⁵. The cam slot has an intermediate horizontal section C⁶, an upper end horizontal section C⁷, a short lower end horizontal section C⁸, an inclined portion C⁹ connecting C⁶ and C⁸ and an inclined portion C¹⁰ 55 connecting C⁶ and C⁷. It will be understood that the plates C³ are slidably mounted in relation to the brackets C² but that their travel is limited by the lower slot C⁴. Each bracket is provided with headed pins C¹¹ C¹², which penetrate the slot 60 C⁴. The movement of the cam plates C³ is limited also by stops C¹⁴ C¹⁵ mounted on the matrix bed A¹. The stops C¹⁴ are at one end of the desired travel of the cam plates C³, as shown in Figures 1, 2, 3 and 9, and the stops C¹⁵ are at 65 the opposite end of the desired movement, as shown for example in Figure 7. Mounted also on the matrix bed A¹, but out of line with the stops C¹⁴ C¹⁵, are two upwardly extending lugs or pins C¹⁶ C¹⁷. These two pins C¹⁶ C¹⁷ are spaced apart 70 both longitudinally and transversely. They are clearly seen for example in Figures 1, 2 and 9.

Each bracket C² has also upwardly offset dog engaging members D D²⁰, positioned one at each end of each bracket, as is clear for example from 75 Figure 1. Concentrically rotatably mounted

upon each cam plate C³ are a pair of dogs D¹ D². Each dog has associated with it one end of the coil spring D³, which tends to force the dog D¹ against the stop pin D⁴ and the dog D² against the stop pin D⁵. Figure 1 indicates the device 5 at the beginning of a stroke, the arrow indicating the direction of the ensuing stroke. Assume that the operator moves the rack C to the left, in the direction of the arrow, the left hand member D engages the dog D¹ and constrains the cam 10 plate C³ to movement in unison with the racks C C¹.

Downwardly extending from the pattern bed B² adjacent one end thereof, and aligned with the path of dogs D² are a pair of dog engaging 15 stops or abutments D⁷. It will be understood that a similar pair, aligned with the path of movement of the dogs D¹, are positioned at the opposite end of the pattern bed, being shown for example as at D⁸ in Figure 7. Also depending 20 from the pattern bed B² at one end thereof is an additional stop or abutment D⁹, as shown in Figures 1 and 2, and a corresponding abutment D¹⁰, as shown in Figure 7, depends from the opposite 25 end of the pattern bed.

Extending inwardly from each cam plate C³, and extending through the lower slot C⁴ of each such cam plate is a pin E. Each such pin projects into a side plate E¹, it being understood that the plates may rotate about the axis of the pins. 30

The side plates E¹ are connected at one end, the left end, referring to the position of the parts as shown in the drawings, by a transverse tie rod E². Reduced ends E³ pass through the side plates E¹ and receive nuts E⁴, whereby the assembly is 35 held together. The shaft of the rod E² is channeled to receive a key E⁵, which abuts at each end against an inner face of one of the side plate members E¹. The key E⁵ is channeled or grooved to receive the edges of a plurality of spacing plates E⁶. Connecting the opposed end of the plates E¹, and extending through the spacing plates E⁶, is an irregularly shaped tie rod E⁷. This is reduced to ends E⁸ and securing nuts E⁹. E¹⁰ is a key 40 similar to E⁵ and also slotted to receive the spacing plates E⁶. 45

Rotatably mounted in the frame thus formed is the circular shaft G. It extends at one end exteriorly outwardly beyond one of the side plates E¹ and has keyed thereon, exterior to such plate, 50 a lever arm G¹ provided with a cam pin G². The shaft also carries a key G³ extending between the inner faces of the side plates E¹. Laterally spaced from the shaft G and also rotatable in the side plates E¹ is an additional shaft G⁴, also with 55 its key G⁵, its exterior lever G⁶ and its cam roller G⁷. Mounted on the shafts G and G⁴ and positioned between the spacing plates E⁶ are a plurality of irregularly shaped Geneva wheels, those on shaft G being indicated as G⁸ and those on the shaft G⁴ being indicated as G¹⁰. These Geneva elements rotate freely about their respective shafts within a predetermined range. Movement is permitted about their respective shafts and keys by the slots G¹¹ in the wheels G⁸ and the 60 slots G¹² in the wheels G¹⁰.

The movement of the relative Geneva members and the spacing of parts which permits the movement are as follows: Figure 4 indicates the parts in starting position. In this position a convex curved surface H on the member G⁸ is opposed 70 to a corresponding concave curved surface H¹ on the member G¹⁰. Further rotation of the member G⁸ in counter-clockwise direction is prevented by the limit projection H². A projection 75

H^3 on the member G^{10} is opposed to a releasing projection A^9 of the latch member A^6 . The racks A^5 keep the parts in the position in which they are shown in Figure 4 and will hold the latch A^6 5 tilted up into the position it is shown in Figure 4. Assume that the parts are moving in the direction of the arrow in Figure 4 and that one of the pattern pins B^1 is depressed it will, as shown in Figure 4, be engaged by a projection H^4 10 of the member G^8 . As the assembly continues its movement toward the left, this will cause a rotation of the particular member G^8 , which is engaged by the pin into the position in which it is shown in Figure 5. This brings another projection H^5 15 of the member G^8 into engagement with the locking member A^{10} of the latch A^6 . This rotation in relation to the shaft G is permitted by the slot G^{11} which clears the key G^3 . Figure 20 illustrates the termination of this rotation of the member G^8 with the latch firmly thrust down 25 into latching position and with the tooth or dog A^7 in engagement with one of the notches A^4 of the bed. This permits the projection H^4 to clear the pin B^1 , so that the assembly can continue its 30 movement to the left. Meanwhile the rotation of the member G^8 has taken the convex surface H out of contact with the member G^{10} and has opposed to it the concave curved surface H^6 . This permits a counter-clockwise rotation of the member G^{10} , whereby its rounded surface H^7 is 35 opposed to the surface H^6 and a further rotation of the member G^{10} is permitted, limited by the engagement of the slot G^{12} with the key. The projection H^3 meanwhile still engages the projection A^9 until, as further rotation continues, to the 40 position shown in Figures 7 and 8, the member G^{10} has rotated so far as to clear the projection A^9 . This is necessary as the assembly continues the movement as a unit to the left but the particular matrix bar A^5 and latch A^6 are left motionless upon the bed. This happens individually as to each matrix strip and latch aligned with any pin B^1 which happens to be depressed. It will be understood that a similar locking and unlocking mechanism is provided for each matrix strip. 45 In case there is any tendency on the part of a given latch A^6 to fail to reach its necessary bottom, latching position, the member or bar E^7 is provided with a flat lower surface E^{20} which rides 50 on the upper surface of the member A^{10} and therefore thrusts it positively down into latching position. Also an inclined upper surface E^{21} of said member E^7 acts as a cam surface to thrust the pin B^1 back into inoperative position. This 55 last mentioned action is clearly shown in Figure 6.

Positioned above the shaft G^4 and also extending between and rotatable in the side plates E^1 is a shaft I , which is cut away as at I^1 , between 60 the side plates E^1 to permit the rotation of the members G^{10} . It is also provided with an outward extension or cam lever I^2 , which is adapted to engage one of the earlier mentioned stops D^9 D^{10} . 65 At the end of the stroke, as shown in Figure 7, this lever I^2 engages the stop D^{10} , which causes a rotation of the shaft I , which moves the cut away portion I^1 into the position in which it is shown in Figures 7 and 8. The shaft I then serves 70 as a stop or lock for preventing clockwise rotation of the member G^{10} since, as shown in Figure 8, in that position the surface H^6 of the member G^8 is opposed to the surface H^7 of the member G^{10} , the immobilization of the member G^{10} prevents any rotation of the member G^8 . The parts 75

are all locked in this position with no parts projecting upwardly enough to engage any pin of the pattern bed which may in the meantime have been again depressed for the next cycle. Figure 7 represents the position of the parts at the end 5 of the stroke, with the cam plate C^3 in engagement with the end stop C^{15} . The cam plate during the forward stroke had projected substantially forwardly of the side plates E^1 but the engagement of the cam plates with the stops C^{15} limited further movement of the cam plates, the side plates E^1 meanwhile continuing their forward movement until the parts reach the position in which they are shown in Figure 10 15. The effect of the relative movement of the cam plates C^3 with the side plates E^1 is to tilt the entire assembly down from the position in which it is shown in Figure 6 to the position in which it is shown in Figures 7 and 20. The side plates E^1 , as earlier mentioned, can 25 tilt or rotate about the pins E . It will be understood that during the forward movement as indicated by the direction of the arrows in Figures 1 and 4, the projections D on the brackets C^2 engage the dogs D^1 of the cam plates C^3 and draw the cam plates forward. Toward the end of the stroke, when the parts reach the position of Figure 7, the dog D^1 is engaged by the stop D^8 and is given thereby a clockwise rotation against the spring D^2 . This permits it to clear the projection D and, the cam plate having reached the end of its movement and being in engagement with the stop C^{15} , the further movement of the racks C draws the whole assembly forward until the side plates E^1 are in the position in which they are shown in Figure 7. Meanwhile this forward movement of the side plates E^1 in relation to the cam C^3 causes a downward tilting of the right hand end of the side plates E^1 and their associated parts, referring to the position of the parts in which they are shown in Figure 7. This tilting is caused by the extension of reduced portions E^{15} of the tie rod E^7 in the cam slot C^5 . The final terminal position of all the parts is 30 indicated in Figure 7 ready for the beginning of the retrograde movement. 35

Assume the beginning of the return stroke with the racks C C^1 moving toward the right. The projection D^{20} engages the dog D^2 and the entire assembly begins to move to the right in the direction of the arrow of Figure 8. This movement continues until the assembly begins to contact the latch members A^6 . Such a contact is indicated in Figure 8. A lower cam face E^{22} of the member E^7 engages the portion A^9 40 of the latch A^6 and rotates it to unlatched position withdrawing the tooth A^7 , as shown in Figure 8. Then the projection E^{23} engages the projection A^{11} of the matrix bar and draws the matrix bar to the right along the bed toward its original position. The various matrix bars are 45 successively freed and picked up in this manner, until the entire battery of bars is moving toward the right. When the assembly approaches its end position the cam plates C^3 engage the stops C^{14} and their further movement is ended. At about the same time the dog D^2 strikes the stop D^7 and is lifted to permit the projection D^{20} to clear, whereby the rest of the assembly 50 can move, in relation to the cam plates C^3 from the position as shown in Figure 8 back to the original position of Figure 1. Just previously the lever I^2 of the shaft I also engages the cam abutment D^9 and is rotated thereby counter- 55

60

65

70

75

clockwise into unlocking position, whereby rotation of the member G^{10} is made possible. In other words, the locking function of the shaft I is for the time being terminated. Also, with the movement of the side elements E^1 in relation to the cam plates C^3 , the reduced portions E^{15} of the member E^7 again ride up the slots C^5 and cause the parts to tilt into the position shown in Figure 9. Just previous to the end of the excursion a reset mechanism comes into place. This reset mechanism includes a cam member K , which rotates about one of the pins E . A cam member is provided with a recessed portion K^1 , which in Figure 9 is shown as engaging the cam roller G^7 of the lever G^6 , which imparts movement to the shaft G^4 . K^2 indicates a cam arm which engages the cam roller G^2 on the lever G^1 , which in turn imparts rotation to the shaft G . K^3 indicates a curved or non-camming portion, which is shown as opposed to the roller G^2 in Figure 9. On one side of the member K is a roller K^4 opposed to the lug C^{16} and on the other is a roller K^5 opposed to the lug C^{17} . With the parts moving to the right, in the direction of the arrow of Figure 9, the roller K^4 engages the stop C^{16} and causes a clockwise rotation of the member K . This causes a clockwise rotation of the shaft G^4 , the shaft G meanwhile being not rotated because of the opposition of the curvature K^3 to the roller G^2 . This rotation of the shaft G^4 returns the member G^{10} to its initial position as shown in Figure 4, the member G^8 being also rotated, when the roller G^2 engages the inclined face of the member K^2 , after the member G^{10} has been set in its position. This ensuing rotation of the shaft G returns the member G^8 to its original position as shown in Figure 4. Thus the entire assembly is back in initial or reset position. The final position is as shown in Figure 1. At the beginning of the ensuing stroke the roller K^5 is opposed to the stop C^{17} and causes a rotation of the member K into the position in which it is shown for example in Figure 9. This also rotates the shafts G and G^4 but this rotation has no effect upon the position of the members G^{10} and G^8 , because this rotation is within the limit permitted by the slots G^{11} G^{12} . The purpose is merely to put the member K into position ready for its resetting function when the assembly again returns to the end of the resetting stroke. Note that the spacing plates E^6 are cut away as at G^{14} and G^{15} to clear the keys G^3 G^5 during rotation of their respective shafts G and G^4 .

It will be realized that whereas I have described and shown a practical and operative device, nevertheless many changes may be made in size, shape, number and disposition of parts without departing from the spirit of my invention. I wish my description and drawings to be taken therefore in a broad sense illustrative and diagrammatic rather than as limiting me to the precise details described and shown. It will be realized for example that my invention may be applied to a variety of uses and its application to use with a pattern bed or for use with matrix strips is intended to be illustrative rather than limiting, except so far as I precisely limit myself by the language of my claims.

Broadly stated, the use and operation of the invention are as follows:

Assume it to be applied to a type casting machine for casting type in response to location

of pattern members. I provide an overlying pattern bed B^2 in which are positioned a plurality of pins B . Below this pattern bed is a matrix bed generally indicated as A^3 upon which slide a plurality of matrix strips generally indicated as A^5 . These strips may be formed with matrices for casting type. I find it convenient for example to employ an ordinary commercial typewriter with any suitable mechanism for depressing the pins B in response to actuation of typewriter keys. Such a structure is shown for example in my Patent No. 1,775,822 issued September 16, 1930. Each matrix strip may have in it impressions corresponding to all the characters of the typewriter. This is preferable but not essential. Assume that the operator has written a line of type. The result is the depression of a plurality of pins, no more than one pin for each matrix strip. When all the pins for the entire line of type have been depressed, the operator then moves the racks $C C^1$ to the left. As each pin is reached it causes, through the mechanism above described, the depression of the latch A^6 for any particular matrix strip. Whereas, at the beginning of the stroke, all the matrix strips move in response to actuation of the racks $C C^1$, each pin causes one of the matrix strips to be released from the actuating mechanism and to be locked positively on the bed by the depression of the latch A^6 into latching position. The successive matrix strips are thus successively anchored in place on the matrix bed. Where no pin is depressed, the matrix strip moves to the end of the excursion and no type impression is cast from it. Whereas it will be understood that the casting mechanism does not form part of the present invention and is not shown at all, I find it practical to employ a casting slot or member whereby, along a given alignment, metal is projected against the matrix strips to cast a line of type. After the line is cast, the operator then moves the racks A^5 to the right and the pick up mechanism operates as above set out in detail, the matrix strips being picked up one by one and returned to the initial position.

I claim:

1. In combination, a supporting bed, a plurality of strips longitudinally movable upon said bed, a latch member associated with each strip and adapted for latching cooperation with said bed, a pattern bed positioned above said strips, pattern elements in said bed, and actuating means for imparting longitudinal movement to the strips, including an actuating carriage and members, rotatably mounted on said carriage, and additional members, rotatably mounted on said first mentioned members, adapted, in response to contact with said pattern elements, to rotate said latched members into latching position in relation to said supporting bed.

2. In combination, a supporting bed, a plurality of strips longitudinally movable upon said bed, a latch member associated with each strip and adapted for latching cooperation with said bed, a pattern bed positioned above said strips, pattern elements in said bed, actuating means for imparting longitudinal movement to the strips, including an actuating carriage, and a plurality of sub-frame members rotatably mounted on said carriage, and members rotatably mounted upon said sub-frame members, adapted, in response to contact with said pattern elements, to rotate said latch members into latching position in relation to said supporting bed.

3. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage and a cam plate, normally movable with said carriage, and a camming connection between said plate and said sub-frame, adapted to tilt said sub-frame in relation to said carriage, in response to relative movement of said carriage and cam plate.

4. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage and a cam plate, normally movable with said carriage, and a camming connection between said plate and said sub-frame, adapted to tilt said sub-frame in relation to said carriage, in response to relative movement of said carriage and cam plate, and means for normally holding said cam plate and sub-frame against relative movement.

5. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage and a cam plate, normally movable with said carriage, and a camming connection between said plate and said sub-frame, adapted to tilt said sub-frame in relation to said carriage, in response to relative movement of said carriage and cam plate, and means for normally holding said cam plate and sub-frame against relative movement, and means for causing their relative movement adjacent the end of the excursion of said carriage.

6. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage, means for normally holding it against movement in relation to said carriage, and means for causing it to rotate in relation to said carriage at a predetermined point in the excursion of the carriage.

7. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage, means for normally holding it against movement in relation to said carriage, and means for causing it to rotate in relation to said carriage at a predetermined point in the excursion of the carriage in one direction, means for causing it to rotate in relation to said carriage at a predetermined point in the excursion of the carriage in the opposite direction.

8. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage,

means for normally holding it against movement in relation to said carriage, and means for causing it to rotate in relation to said carriage at a predetermined point in the excursion of the carriage, and latch actuating means positioned on said sub-frame, and means for normally holding them against movement in relation to said sub-frame.

9. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage, means for normally holding it against movement in relation to said carriage, and means for causing it to rotate in relation to said carriage at a predetermined point in the excursion of the carriage, and latch actuating means positioned on said sub-frame, and including a pair of engaging Geneva elements, and means for normally holding them against rotation in relation to said sub-frame.

10. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage, means for normally holding it against movement in relation to said carriage, and means for causing it to rotate in relation to said carriage at a predetermined point in the excursion of the carriage, and latch actuating means positioned on said sub-frame, including engaging Geneva elements, one of said Geneva elements having a cam portion adapted to engage an opposed cam portion of the latch and, when rotated, to thrust the latch into latching position.

11. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage, means for normally holding it against movement in relation to said carriage, and means for causing it to rotate in relation to said carriage at a predetermined point in the excursion of the carriage, and latch actuating means positioned on said sub-frame, including engaging Geneva elements, one of said Geneva elements having a cam portion adapted to engage an opposed cam portion of the latch and, when rotated, to thrust the latch into latching position, the other Geneva element including a portion adapted to engage an opposed portion of the latch and to hold the latch in unlatched position.

12. In combination, a supporting bed, a member longitudinally movable upon said bed, a latch associated with said member and adapted for latching cooperation with the bed, and means for actuating said latch in response to endwise movement of said member, including an actuating carriage, a sub-frame pivoted on said carriage, means for normally holding it against movement in relation to said carriage, and means for causing it to rotate in relation to said carriage at a predetermined point in the excursion of the carriage, and latch actuating means positioned on said sub-frame, including engaging Geneva elements, one of said Geneva elements having a cam portion adapted to engage an opposed cam por-

tion of the latch and, when rotated, to thrust the latch into latching position, the other Geneva element including a portion adapted to engage an opposed portion of the latch and to hold the 5 latch in unlatched position, a stop member positioned above the supporting bed and the longitudinally movable member and adapted to engage the first mentioned of said Geneva members and to rotate it into latch actuating position in 10 response to a movement of the actuating carriage and sub-frame in one direction.

13. In combination, a supporting bed, a member longitudinally movable upon said bed, a latch associated with said member and adapted for 15 latching cooperation with the bed, and means for actuating said latch in response to endwise movement of said member, including an actuating carriage, a sub-frame pivoted on said carriage, means for normally holding it against movement 20 in relation to said carriage, and means for causing it to rotate in relation to said carriage at a predetermined point in the excursion of the carriage, and latch actuating means positioned on said sub-frame, including engaging Geneva elements, one of said Geneva elements having a cam portion adapted to engage an opposed cam portion of the latch and, when rotated, to thrust the latch into latching position, the other Geneva element including a portion adapted to engage 25 an opposed portion of the latch and to hold the latch in unlatched position, a stop member positioned above the supporting bed and the longitudinally movable member and adapted to engage the first mentioned of said Geneva members and to rotate it into latch actuating position in 30 response to a movement of the actuating carriage and sub-frame in one direction, said stop member being out of contact with said Geneva member when the actuating carriage is 35 moving in the opposite direction.

14. In combination, a supporting bed, a member longitudinally movable upon said bed, a latch associated with said member and adapted for latching cooperation with the bed, and means for 40 actuating said latch in response to endwise movement of said member, including an actuating carriage, a sub-frame associated with said carriage,

a pair of engaging Geneva members rotatably mounted on said sub-frame, shafts on which said Geneva members are rotatably mounted, limit members on said shafts, said Geneva members being provided with segmental apertures in which 5 said limit members are adapted to move.

15. In combination, a supporting bed, a member longitudinally movable upon said bed, and means for moving it, a latch associated with said member and adapted for latching cooperation with said bed, and means for actuating said latch in response to endwise movement of said member, including an actuating carriage, an intermediate member pivoted to said carriage, rotatable latch actuating means mounted upon said intermediate 10 member, and means for actuating said means in response to endwise movement of said carriage.

16. In combination, a supporting bed, a member longitudinally movable upon said bed, and means for moving it, a latch associated with said member and adapted for latching cooperation with said bed, and means for actuating said latch in response to endwise movement of said member including an actuating carriage, an intermediate member pivoted to said carriage, rotatable latch actuating means mounted upon said intermediate 20 member, means for actuating said means in response to endwise movement of said carriage, and independent means for rotating said intermediate member in relation to said carriage.

17. In combination, a supporting bed, a member longitudinally movable upon said bed, and means for moving it, a latch associated with said member and adapted for latching cooperation with said bed, and means for actuating said latch in response to endwise movement of said member including an actuating carriage, an intermediate member pivoted to said carriage, rotatable latch actuating means mounted upon said intermediate member, means for actuating said means in response to endwise movement of said carriage, and independent means for rotating said intermediate member in relation to said carriage, including camming means normally movable with said carriage.

CHESTER A. MACOMIC.
